UNITED STATES PATENT OFFICE.

EUGENE ORA DANIELS, OF TOLEDO, OHIO.

HEATING STOVE.

Application filed October 17, 1923. Serial No. 669,130.

To all whom it may concern:

Be it known that I, EUGENE ORA DANIELS, a citizen of the United States, residing at Toledo, in the county of Lucas and State of Ohio, have invented certain new and useful Improvements in Heating Stoves, of which the following is a specification.

In carrying out the present invention it is my purpose to provide a stove of the heating type wherein the same may employ gaseous fuel in the operation thereof for thereby overcoming the numerous dangers that are ever present in the use of stoves of the liquid fuel or coal-burning type.

It is an additional purpose of this invention to provide such a stove wherein a great amount of heat will be produced by the burning of a relatively small amount of fuel for thereby lessening the operating expense of stoves of this character.

It is a still further purpose of my invention to substantially improve and simplify the general construction of stoves of the present nature.

With the above and other purposes in view as the invention will be better understood, the same comprises the novel form, combination and arrangement of parts hereinafter more fully described, shown in the accompanying drawings and claimed.

In the drawings wherein like reference characters indicate corresponding parts throughout the several views,

Figure 1 is a front elevational view of my improved stove, the front wall thereof being broken away at its upper and lower ends for disclosing the relative positioning of the burners and the air discharge pipes respectively,

Figure 2 is a vertical transverse sectional view thereof,

Figure 3 is an enlarged top plan view of the burner arrangement employed in conjunction with this stove,

Figure 4 is an enlarged top plan view partly in cross section of a slightly modified form of burner, and

Figure 5 is an enlarged fragmentary side elevational view of the air and gas mixer employed for use in conjunction with the type of burner shown in Figure 4.

Now having particular reference to the drawings, my novel heating stove embodies the provision of a stand 5 that is equipped with integral supporting legs 6. This stand is in top plan of a somewhat oval-shaped

configuration and is formed with integral upstanding flanges 7 within which set the lower ends of relatively long oval-shaped drums 8 and 9, respectively, that are secured to said flanges through the medium of rivets or other suitable fastening means 10. Upon the upper ends of these drums 8 and 9 there is positioned a cover 11 that is formed at its rear side and above the rearmost drum 9 with a perforated open ended dome-shaped hood 12 that is in turn provided with air outlet openings 13, Figures 1 and 2.

The portions of the stand 5 beneath the drums 8 and 9 are open as clearly shown in said Figures 1 and 2 and extending through the opening in the stand beneath the foremost drum 8 are a plurality of gas burners 14 arranged in horizontally spaced relation as more clearly shown in the top plan view, Figure 3. Each of these burners is of somewhat conventional form that is comprising a central circular chamber 15 in communication with an outer hollow ring portion 16 through the medium of by-passes 17, the top walls of the central chamber and outer hollow ring portion being perforated as clearly shown, for obvious purposes. Each of these burners also includes an air dome 18 that has communication with the central chamber 15 through the medium of a short pipe section 19. Entering the air domes 18 of the two end burners are gas outlet nipples 20 leading from a valved pipe 21 that is in communication with a gas supply pipe 22. Leading into the air dome of the central burner is the outlet end 23 of another valved pipe 24 that is also in communication with said gas supply pipe 22, it being obvious that this arrangement allows either one, two or all of the burners to be employed as the occasion demands.

Within the foremost drum 8 and directly above a clean-out opening 25 that is normally closed by a suitable form of door 26 is a flame spreader 27 that is secured within the air drum 8 and spaced from the walls thereof by brackets 28, Figure 2.

Within the rearmost drum 9 is a relatively large air pipe 29 that is closed at its lower end and terminates slightly above the opening in the stand 5 beneath said drum 9 the upper end of this pipe extending through an opening in said dome-shaped hood 12 and connecting with the usual flue or chimney 110 of the building. Communicating at one end adjacent the lower end of said pipe 29 and

at opposite sides thereof are other pipes 30 vertically arranged within the drum 9 the upper opposite ends thereof terminating in necks 31 that engage within the foremost drum 8 for receiving the heated air from this drum and conveying the same downwardly and thence into the pipe 29 then upward and downward and then again upward travel of the heated air consequently thoroughly heating the front and rear drums 8 and 9 which will consequently give off a great amount of heat even though only one of the burners be employed, it being manifest that the air passing upwardly into the drum 9 will be heated by the pipes 29 and 31 and consequently will pass directly through the openings 13 in the hood 12 and outwardly through the ends thereof.

In Figure 4 I have shown a slightly modified form of burner that may be employed in conjunction with this present heating stove and in this instance, the burner includes a central circular chamber 32 in communication with a spaced hollow and circular rim 33 through the medium of by-passes 34, the said circular chamber 32 being also joined to the hollow rim 33 through the medium of a neck 35. Within a screw-threaded opening in the hollow rim 33 as well as an aligned circular opening in said neck 35 is the long screw-threaded end of a pipe 36. The pipe 36 of each of the burners has communication with a horizontal pipe 37, Figure 5, one end thereof terminating in an elbow 38 that is open at its lower end as shown for providing an air inlet, the opposite end of this pipe 37, not shown, is preferably closed. Engaging through an opening in said elbow 38 is a gas nipple 39 that

has communication with a horizontal gas pipe 40 that leads to a source of gas supply it being obvious that the gas passing outwardly of the nipple 39 will create a suction within the elbow 38 and consequently draw in a charge of air.

In view of the foregoing it is apparent that I have provided a highly novel and useful form of heating stove and one that will effectively dispense with the widely used liquid and solid fuel burning types of stoves, and one, I believe, that will meet with all of the requirements for a successful commercial use.

Minor changes may be made within the invention without departing from the spirit and scope of the appended claim.

Having thus described my invention, what I claim as new and desire to secure by Letters Patent is:—

In a heating stove of the class described, 60 a supporting stand, a pair of open ended drums arranged upon said supporting stand and in close relationship with each other, said supporting stand being provided with openings registering with the lower open 65 ends of said heating drums, a top for the upper open ends of said drums, burners arranged within one of said drums, a vertical pipe arranged within the other of said drums and being open at its lower end, and branch 70 pipes upon opposite sides of said first mentioned pipe and having communication therewith adjacent its lower end, said branch pipes extending upwardly within the drum and having their opposite ends terminating within the other of said drums.

In testimony whereof I affix my signature.
EUGENE ORA DANIELS.
